[57] CLAIM

The ornamental design for a combined container and applicator for liquid shoe polish or similar article, as shown.

DESCRIPTION

FIG. 1 is a left side elevational view of a combined container and applicator for liquid shoe polish or similar article showing my new design;

FIG. 2 is a front elevational view thereof;

FIG. 3 is a top plan view thereof;

FIG. 4 is left side elevational view of the uncapped body portion thereof;

FIG. 5 is a front elevational view of the uncapped body portion thereof;

FIG. 6 is a rear elevational view of the uncapped body portion thereof;

FIG. 7 is a top plan view of the uncapped body portion thereof; and

FIG. 8 is a bottom plan view thereof.
